CLAIM

The ornamental design for an electrical tester, as shown and described.

DESCRIPTION

FIG. 1 is a front perspective view of a first construction of an electrical tester.

FIG. 2 is a front view of the electrical tester of FIG. 1.

FIG. 3 is a rear view of the electrical tester of FIG. 1.

FIG. 4 is a left side view of the electrical tester of FIG. 1.

FIG. 5 is a right side view of the electrical tester of FIG. 1.

FIG. 6 is a top view of the electrical tester of FIG. 1; and,

FIG. 7 is a bottom view of the electrical tester of FIG. 1.

The ornamental design which is claimed is shown in solid lines in the drawings. The portions of the design shown in broken lines are included for the purpose of illustrating environment and form no part of the claimed design.

1 Claim, 6 Drawing Sheets
